CLAIM

The ornamental design for a clasp, as shown and described.

DESCRIPTION

FIG. 1 is a perspective view of the clasp;

FIG. 2 is another perspective view thereof;

FIG. 3 is a front view thereof, the back view being a mirror image thereof;

FIG. 4 is a top view thereof;

FIG. 5 is a bottom view thereof;

FIG. 6 is a right side view thereof; and,

FIG. 7 is a left side view thereof.

The dash dot lines immediately adjacent to the claimed areas in the views represent the boundaries of the claimed design. The dashed lines in the figures illustrate the portions of the design that form no part of the claimed design. None of the broken lines form any part of the claimed design.
